UNITED STATES PATENT OFFICE

KARL C. RANDALL, OF EDGEWOOD, PENNSYLVANIA, ASSIGNOR TO WESTINGHOUSE ELECTRIC & MANUFACTURING COMPANY, A CORPORATION OF PENNSYLVANIA

CIRCUIT BREAKER

Application filed April 4, 1930. Serial No. 441,513.

My invention relates to circuit breakers and particularly to circuit breakers for controlling the operation of motors, electric lamps and similar apparatus.

5 An object of my invention is to provide a circuit breaker, including a current-responsive device having substantially fixed operating characteristics and operative for opening the circuit under predetermined current 10 or load conditions, with means for rendering the current-responsive device effective for opening the circuit breaker under current or load conditions greater or less than the said predetermined current or load conditions.

Another object of my invention is to provide a circuit breaker having relatively large capacity that comprises a plurality of relatively small circuit-breaker units each provided with a current-responsive trip device having definite characteristics and relatively low capacity and wherein the current supplied to the current-responsive devices may be divided uniformly between them or proportioned in accordance with any predetermined values.

A further object of my invention is to provide a circuit breaker comprising a plurality of circuit-breaker units connected in parallel in each circuit to be operated by a manually operable handle that is trip-free of the circuit breaker units and wherein the current supplied to the current-responsive trip devices for each circuit breaker may have a predetermined value, thereby rendering all of the circuit breakers simultaneously operable to trip to open position, under predetermined overload or short-circuit conditions.

40 A further object of my invention is to provide a polyphase circuit breaker wherein a plurality of current-responsive circuit breakers are connected in parallel in each phase and wherein the current supplied to the current-responsive devices of each circuit breaker may be proportioned in predetermined values and wherein all of the circuit breakers may be manually operated by a handle that is trip free of them.

50 A further object of my invention is to pro-

vide a circuit breaker having the above noted characteristics wherein the transformers serve as current-limiting agents; thereby limiting the current passing through the circuit breaker at the time of opening under 55 severe overload of short-circuit surges.

These and other objects that will be made apparent throughout the further description of my invention are obtained by circuit-breaker apparatus hereinafter described and 60 illustrated in the accompanying drawings, wherein;

Figure 1 is a longitudinal section through a circuit breaker embodying features of my invention, portions of the circuit breaker being shown in elevation;

Fig. 2 is a plan view of the circuit-breaker apparatus shown in Fig. 1, the housing being shown in section;

Fig. 3 is a diagram showing the manner 70 in which the bimetal thermal element of a single circuit-breaker unit is connected to an auto-transformer, for rendering the circuit breaker operable to trip open under a load less than that for which the thermal 75 element is designed to operate;

Fig. 4 is a view, similar to Fig. 3, showing the manner in which an auto-transformer is connected to the thermal-element for rendering it operable to trip only under 80 a load greater than that for which the thermal element is designed to operate;

Fig. 5 is a diagram showing a pair of thermal elements of separate circuit-breaker units connected to an auto-transformer for 85 distributing the current to the thermal elements in predetermined proportions;

Fig. 6 is a diagram, similar to that of Fig. 5, showing the manner in which three thermal elements of separate circuit breakers are connected to two auto-transformers for distributing the current between the thermal elements in predetermined proportional values;

Fig. 7 is a diagram, similar to that of Fig. 5, illustrating the manner in which four thermal elements of separate circuit breakers are connected to three auto-transformers for distributing the current between the 100

thermal element in predetermined proportional values and

Fig. 8 is a diagram showing the manner in which 9 or more circuit breaker units 5 may be connected in a three phase circuit in such manner that the thermal elements of the separate circuit breakers are connected to auto-transformers for uniformly distributing the current supplied thereto.

10 In Figs. 1 and 2, I have shown my invention applied to a current-responsive circuit-breaker unit, such as is disclosed in Patent No. 1,794,901, issued to O. S. Jennings, and assigned to the assignee of this application.

15 Briefly, each circuit-breaker unit comprises an insulating base 9 having a recess 11 in which a stationary contact 12 is mounted and which is adapted to be engaged by a movable contact 13 carried upon a switch 20 arm 14 that is pivoted, at 15, upon a sheet-metal frame or bracket 16 which is mounted on the base 9 within the notch 11. The switch arm 14 is operated by a pair of toggle links 17 and 18, that are pivoted together by a knee pivot 19. The link 17 is pivotally mounted on a shaft 21 which is carried by the switch arm 14, and the link 18 is pivotally seated in a notch 22 of V shape provided in a releasable carrier 23 that is pivotally mounted on the frame 16 for rotation 25 about a shaft 24.

20

25

30

The carrier 23 is releasably retained in the operable position shown in Fig. 1 by a bimetal thermal element 26 of U shape and is diagrammatically illustrated in Figs. 3 to 8, inclusive. An operating lever 27 is mounted for rotation about the shaft 28 that is secured to the frame 16, and is provided with an insulating handle 29 by means of which the switch may be manually operated. A tension spring 31 connects the outer end of the operating lever 27 to the knee pivot 19 of the toggle links 17 and 18 and serves to move the toggle links to the "made" or straightened positions shown in Fig. 1 wherein the knee pivot 19 lies slightly above a line connecting the shaft 21 and the pivot seat of the link 18.

When the toggle is in the "made" position, the contact of the switch arm 14 is releasably retained in closed position, and, when the operating handle 29 has been moved downwardly a sufficient distance, the spring 31 causes the toggle to collapse and move the switch arm 14 to open position with a snap action. By reason of this construction, the switch arm is actuated to open and to closed position by the over center spring 31, when the switch or circuit breaker is manually operated through the medium of the handle 29.

The spring 31 also tends to move the carrier 23 in a clockwise direction, and, regardless of the position of the operating handle, does actually move the carrier 23

when the thermal element 26 has been heated sufficiently to move the latch 32, that is secured to its outer end, out of engagement with the free end of the carrier 23.

The bimetal element may be proportioned to release or trip the circuit breaker to open position in response to a predetermined overload or a short-circuit condition and to retain the circuit breaker in closed position so long as the value of the current passing through the circuit breaker remains below a predetermined amount.

It will be understood that the bimetal element is normally connected in series with the circuit-breaker contacts and is heated by the current flowing through the circuit breaker contacts to the motor or lamp circuit to which the circuit breaker is connected. It will be further understood that the circuit breaker is trip-free of the handle and, therefore, the handle cannot interfere with the opening movement of the circuit breaker in response to an overload or short-circuit condition, regardless of its position, or whether it is being held by the operator.

In practice, it has been found that a small circuit breaker of the character disclosed in the above-noted copending application and described herein, may be conveniently and economically provided with thermal elements capable of causing the circuit breaker to open under currents slightly in excess of 15 amperes or 30 amperes, depending upon the predetermined capacity of the thermal element employed.

Circuit breakers having a current-carrying capacity of 30 amperes may, therefore, be provided with a 15-ampere-capacity thermal element for use in distributing panels of house-wiring circuits, and with thermal elements of 30-ampere capacity when used as entrance circuit breakers. Because of the large demand for circuit breakers of the 15 and 30-ampere capacity and because the circuit breaker unit is the same in both cases, with the exception of the thermal element, the circuit breakers may be manufactured on a quantity-production basis, with the result that the manufacturing cost is materially reduced.

There are, however, certain fields of activity that require circuit breakers which will open the circuit under current values considerably less than 15 amperes, and there is also a demand for circuit breakers for circuits having apparatus that requires protection at current values considerably above 30 amperes.

It is an object of my invention to provide a circuit breaker wherein standard circuit-breaker units having the characteristics of circuit breakers above described and which may be manufactured on a quantity-production basis, may be used in circuits requiring protection at current values considerably less

and considerably greater than those for which the standard circuit breaker is designed.

In Fig. 3, I have diagrammatically shown a circuit breaker having a bimetal thermal element 26 that is designed to cause the circuit breaker to open when an overload slightly exceeding 15 amperes occurs. In order to adapt the circuit breaker for use in a circuit wherein the current must not exceed 3 amperes, for example, I have provided an auto-transformer which may be of any preferred construction and may have a winding 33 and the usual iron core (not shown).

The bimetal element 26 is connected, at one terminal, to one end of the winding 33 and to the switch arm 14, and the other terminal of the bimetal element is connected to a tap connection 34 that may be connected to the winding 33, at any predetermined point, to obtain the desired operating result.

The auto-transformer employed is of such design that it will, at operating voltage, permit the required current to flow therethrough with but little impedance. By reason of the manner in which the thermal element 26 is connected to the winding 33, a circuit is established which includes the thermal element and through which current will circulate having a value determined by the relative position of the tap connection 34 with respect to the coils of the winding 33. If it is desired to cause the thermal element 26, which is designed to trip the circuit breaker to open position under a load slightly greater than 15 amperes, to trip the circuit breaker to open position when the current value slightly exceeds three amperes, the tap 34 is adjusted to include sufficient turns of the winding 33 between the terminals of the thermal element to set up a current through the thermal element corresponding to that required to cause its operation under a load slightly greater than 15 amperes. By reason of this arrangement of the bimetal element and its associated auto-transformer, a 15-ampere-capacity thermal element may be used to operate under a current value of three or less amperes, if desired.

Since the auto transformer is connected in series with the circuit breaker, it also serves to limit the current passing through the circuit breaker at the time of opening under severe overload or short-circuit surges.

In Fig. 4, I have diagrammatically illustrated a thermal bimetal element of 30-amperes capacity, so connected to an auto-transformer 33 that it may be used in a circuit breaker that is connected in a circuit normally carrying 60 amperes. In this construction, the feed conductor 35 is so connected to the tap connection 34 that the feed

conductor may be connected to the winding 33 at any desired point intermediate the ends of the winding. The terminals of the bimetal element 26 are connected across the extreme ends of the winding 33. In this arrangement, the current of 60 amperes may be so divided that substantially 30 amperes flows through the bimetal element 26 and substantially 30 amperes flows through the right-hand end of the winding 33. By adjusting the tap connection 34 to certain positions on the winding 33, the proportion of the current supplied to the thermal element 26 may be varied, and, therefore, the circuit breaker may be made to trip open by current values ranging from 30 to 60 amperes. The auto-transformer, in this case should, however, be designed to pass 60 amperes of current with a minimum of impedance.

In Fig. 5, I have illustrated the manner in which two circuit-breaker units may be connected in parallel in a circuit for doubling the capacity of the circuit breaker. For instance, if two 30-ampere-capacity circuit breakers are connected in parallel, they will function to open the circuit when the load exceeds 60 amperes, provided the current is equally divided between them. Since it is difficult to manufacture two circuit breakers that have exactly the same contact resistance and the same thermal element resistance, it is necessary to determine their relative conductivity and provide means for equalizing the current supplied to each of them and their thermal elements in order that one of them shall not carry more of the load than the other and thus cause premature opening by reason of over-heating. I have, therefore, provided an auto-transformer winding 33 with a tap connection 34 to which the feed conductor 35 is connected, the tap connection being located at the point where the required distribution of the current is accomplished.

It will be understood that, where a plurality of circuit breakers of the "trip-free of the handle" type are utilized, a single operating handle 29 is provided that is connected to an insulating bar 36 which is connected to the operating levers 27 of the several circuit breakers, as indicated in Fig. 2, wherein, three circuit breakers are shown connected in parallel in a single circuit.

In the event that one of the thermal elements 26 releases its circuit breaker before the other circuit breaker is opened, the sudden increase of current through the other circuit breaker and thermal element will almost instantly cause the remaining circuit breaker to open because it is already on the verge of opening at the time the first circuit breaker is released.

By reason of this arrangement of the thermal elements of two circuit breakers with

an auto-transformer, it is possible to connect a 15-ampere thermal element and a 30-ampere thermal element in such manner that they will both function to open the circuit 5 simultaneously, under a predetermined load condition.

In Figs. 6 and 7, I have illustrated the manner in which a group of three and four 10 separate circuit-breaker units may be connected in a single circuit, and the current distributed as desired, through the medium of auto-transformers, to obtain the desired operating characteristics of the circuit breaker. By combining three circuit breakers, each having 30-ampere-capacity thermal elements, a 90-ampere circuit breaker may be produced and, by combining four 30-ampere circuit breakers of 30-ampere capacity, a 120-ampere circuit breaker may be obtained. 15

In Figs. 1 and 2, I have shown a circuit breaker of the 90-ampere-capacity type which comprises three 30-ampere-capacity circuit-breaker units. The units are mounted 20 within a metal housing 37 having a cover 38 that may be sealed in closed position and is provided with a slot 39, through which the operating handle 29 projects. The two auto-transformers 33 required for the arrangement illustrated diagrammatically in Fig. 6 are mounted in the same housing with the circuit-breaker units and are, therefore, protected from external objects and from tampering therewith. 25

It has been found that a circuit breaker that has been constructed by combining two or more 15 or 30-ampere circuit-breaker units is considerably less expensive than a single circuit breaker having a capacity 30 equal to that of the combined units. A circuit breaker of relatively large capacity usually requires a blow-out coil or other relatively expensive means for extinguishing the arc drawn between the contacts when 35 the circuit breaker opens. In the case of the small circuit breaker units, connected in parallel in a single circuit, the arcs drawn are relatively small and are readily extinguished without the necessity for a blow-out 40 coil or like extinguishing device. As briefly pointed out, because of the quantity production of the small units, the manufacturing cost is materially reduced. 50

In Fig. 8, I have disclosed the manner in 55 which a three-phase circuit breaker is arranged by providing three parallel-connected circuit-breaker units for each phase of the circuit and by providing the necessary auto-transformers 33 for distributing the 60 current between the circuit breakers of each phase. In this arrangement, nine circuit-breaker units and six auto-transformers 33 are required. The operating bar 36 extends 65 across the circuit-breaker units and is connected to each of the operating levers of the

nine circuit breakers. Since the individual circuit-breaker units are all trip-free of the handle, they may trip open without effecting the other circuit breakers connected in the circuit. 70

It will be understood that, while I have shown the current-responsive trip devices of the circuit breakers associated with auto-transformers for the purpose of distributing the current in predetermined proportion between the several trip devices, other means may be provided for distributing the current between the devices, such as a rheostat or some other form of transformer wherein the primary and secondary windings are 80 separate and of the inductive type. 75

Other forms of current-responsive devices may also be used, and various changes, modifications, substitutions, additions and omissions may be made in the apparatus illustrated without departing from the spirit and scope of my invention as set forth in the appended claims. 85

I claim as my invention:

1. The combination with a circuit breaker having a current-responsive thermal trip-device connected in series with the contacts thereof, of an auto-transformer connected in series with the circuit-breaker contact for controlling the supply of current to the said trip-device. 90

2. The combination with a plurality of circuit breakers each having a current-responsive thermal trip-device connected in series with the contacts of its respective circuit breaker, the said trip-devices being connected in parallel, of means for dividing the current among the current-responsive devices in predetermined proportions. 100

3. The combination with a plurality of circuit breakers each having a current-responsive thermal trip-device in series with its respective circuit breaker, of means, including auto-transformers for dividing the current among the current-responsive devices in predetermined proportions. 105

4. The combination with a plurality of circuit breakers connected in parallel in a single circuit and each having a current-responsive thermal trip-device connected in series with the contacts of its respective circuit breaker, the said trip-device being connected in parallel, of means for supplying current to the trip devices in predetermined proportions. 110

5. The combination with a plurality of circuit breakers connected in parallel to a single circuit and each having a current-responsive thermal trip device in series with the corresponding circuit breaker, of means for supplying current to the trip device in predetermined proportions, and a manually operable means for simultaneously operating the circuit breakers that is trip-free from all of the said circuit breakers. 115

6. A polyphase circuit breaker comprising a plurality of circuit breakers connected in parallel in each phase and having a common manually operable means for operating the circuit breakers that is trip free from all of them, a separate current-responsive thermal trip-device for each circuit breaker for each phase, and means for supplying current to the said trip-devices in predetermined proportions.

7. In a circuit interrupter, a plurality of switch arms connected in parallel in a single circuit, a single operating means for normally actuating all of said switch arms, a plurality of current-responsive thermal trip elements each connected in series with one of said switch arms, and means for dividing the current among said trip elements in predetermined proportions.

20 8. In a circuit interrupter, a plurality of switch arms connected in parallel in a single circuit, a single operating means for normally actuating all of said switch arms, a plurality of current-responsive thermal trip elements each connected in series with one of said switch arms and all of said switch arms being caused to open substantially simultaneously upon the flow of a predetermined current through one of said trip elements, and a transformer for causing current to flow through said trip elements in predetermined proportions.

9. In a circuit interrupter, a plurality of switch arms connected in parallel in a single circuit, a single operating means for normally actuating all of said switch arms to both open and closed positions and said switch arms being movable to open position irrespective of the position of said operating means, a plurality of current-responsive thermal trip elements each connected in series with one of said switch arms and all of said switch arms being caused to open substantially simultaneously upon the flow of a predetermined current through one of said trip elements, and an auto-transformer for dividing the current flowing in said single circuit between said trip elements in predetermined proportions.

50 In testimony whereof, I have hereunto subscribed my name this 31st day of March, 1930.

KARL C. RANDALL.
